UNITED STATES PATENT OFFICE.

GEORGE W. BEATTY, OF DECATUR, ILLINOIS.

FUSE-SETTING MACHINE.

Application filed January 24, 1928. Serial No. 249,169.

(GRANTED UNDER THE ACT OF MARCH 3, 1883, AS AMENDED APRIL 30, 1928; 370 O. G. 757.)

The invention described herein, if patented, may be manufactured and used by or for the Government for governmental purposes without the payment to me of any royalty thereon.

The subject of this invention is a fuse setting machine.

In machines for setting the fuses of projectiles there is no provision for locking the projectiles to the machines until the fuse is completely set. In anti-aircraft gunnery the target is in range during a very short period and the necessity of delivering a maximum rate of fire has produced a tendency on the part of the personnel to prematurely withdraw the round from the fuse setting machine. The fuse of the round is therefore incorrectly set and a condition arises that despite the most careful preparation of data and the greatest accuracy in laying the gun renders the adjustment of fire impossible.

The object of this invention is to provide means for preventing the premature withdrawal of the round from the fuse setting machine.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view of my improved fuse setter in its normal position;

Fig. 2 is a similar view of the machine with a round inserted;

Fig. 3 is a detailed sectional view on the lines 3—3 of Fig. 2;

Fig. 4 is a detailed sectional view on the lines 4—4 of Fig. 2 showing the fuse engaging levers in elevation;

Fig. 5 is a side view of the time fuse for which the machine is designed.

Referring to the drawings by numerals of reference:

The mechanism constituting the invention is embodied as an improvement in the fuse setting machine disclosed in my prior Pat-

ent No. 1,640,392 of August 30, 1927. That machine is of the type which is provided with two relatively rotatable adjusting members, a crank for independently rotating one member which is coupled to the time ring of the fuse and a worm gear for rotating the other member which is coupled to a fixed part of the fuse. The adjustment of the fuse is effected by causing the time ring adjusting member to carry out two complete revolutions while the other member is either stationary or may be under continuous operation.

The machine consists of a housing 6 in which two adjusting members 7 and 8 are independently rotatable about the axis of the machine. The member 7 is adapted to be coupled to the lug 9 of the rotatable time ring 10 by means of levers 11 while the member 8 is adapted to be coupled to the lug 12 on a fixed part of the fuse by means of levers 13.

In order that the fuse setting machine may be capable of engaging and setting the fuse irrespective of the position of the lugs with relation to each other or to the machine the adjusting member 7 is directly connected to a crank 14 for rotating said member until its levers 11 pick up the lug 9 on the time ring and place it in a predetermined position while at the same time a rotational movement will be imparted to the round until the fixed lug 12 snaps into engagement with the levers 13 of the adjusting member 8. In order to insure that the round will be rotated sufficiently for the fixed lug to pick up the levers on the member 8 it is necessary to move the crank through two complete revolutions.

A worm 15 serves for imparting to the adjusting member 8 and the fixed lug 12 of the round an angular position relative to the predetermined position of the time ring 10 which corresponds to the fuse range. Disposed axially within the adjusting member 7 is a spring pressed plunger 16 splined to said member by means of a latch 17 which is pivoted in the member and arranged to engage behind the cap 18 of the round, when the round, on being fully inserted has forced the plunger to the position shown in Fig. 2. The round is thus securely locked to the fuse setting machine and can not be withdrawn until the operation of setting the fuse is completed as will now be described.

In order to prevent actuation of the crank 14 until such time as a round is inserted there is mounted in the housing 6 a spring pressed bolt 19 which is normally engaged in a slot 20 in the adjusting member 7. The bolt is disengaged from the member 7 upon insertion of a round by means of a cam arm 21 disposed in the slot 20 and formed on a ring 22 which is mounted on the plunger 16 and connected thereto by a torsion spring 23. The cam arm 21 completes the connection between the ring 22 and the adjusting member 7 so that they will be rotated together but the slot 20 is of sufficient width to permit a slight relative movement as indicated in Fig. 3 at the termination of the final revolution of the adjusting member. This relative movement is of a positive character being effected by the bolt 19 which is permitted to enter a groove 24 in the adjusting member 7 during the termination of the second revolution of the adjusting member, but is prevented from entering the groove 24 during the first revolution through the cooperation of the crank 14 and a Geneva wheel 25, as previously described in the patent previously referred to.

The relative movement of the ring 22 is utilized to release the latch 17 from the round and to this end is provided with a cam tooth 26 which strikes the intermediate surface 27 of the latch and holds the latch disengaged during the initial restoration of the plunger 16 when the round is removed. When the plunger has moved sufficiently to cause the cam arm 21 to clear the bolt 19 and permit the torsion spring 23 to realine it with the bolt the head 28 of the plunger will have passed over the free end of the latch and will serve to hold it in the disengaged position.

40 I claim:

1. A fuse setting machine embodying a rotatable adjusting member, a bolt normally engaged with the adjusting member to prevent movement thereof, an ammunition holding latch pivoted to the adjusting member, a plunger splined to the adjusting member by the latch, and adapted to be retracted when struck by a round of ammunition introduced

into the machine, a cam member mounted on the plunger for disengaging the bolt when the plunger is retracted and means whereby the bolt may actuate the cam member, and trip the latch on termination of the setting movement of the adjusting member.

2. A fuse setting machine embodying a rotatable adjusting member, a bolt normally engaged with the adjusting member to prevent movement thereof, an ammunition holding latch pivoted to the adjusting member, a plunger splined to the adjusting member, and adapted to be retracted when struck by a round of ammunition introduced into the machine, a cam member mounted on the plunger for disengaging the bolt when the plunger is retracted and means whereby the bolt may actuate the cam member and trip the latch on termination of the setting movement of the adjusting member.

3. A machine for setting the fuse of a round of ammunition embodying a rotatable adjusting member, locking means for normally holding said member against movement, round actuated means within the adjusting member for disengaging the locking means and means arranged to be tripped by the round actuated means for locking a round of ammunition to the adjusting member.

4. A machine for setting the fuse of a round of ammunition embodying an adjusting member, a latch for locking a round to said member, round actuated means for uncovering the latch and means associated with said round actuated means for tripping the latch.

5. A machine for setting the fuse of a round of ammunition embodying an adjusting member, means for locking a round to said member, and means operable by completion of the setting movement of the adjusting member for disengaging the locking means.

6. In a fuse setting machine, an adjusting member and means carried by said member for locking a round of ammunition thereto when said member is operated.

GEORGE W. BEATTY.
